J. D. MAIL
CARBURETOR OR VAPORIZER PROVIDING MEANS FOR EASY STARTING OF INTERNAL
COMBUSTION ENGINES
Filed Aug. 24, 1923

Inventor
James Douglas Mail
By
B. Singer, Atty.

UNITED STATES PATENT OFFICE.

JAMES DOUGLAS MAIL, OF DURBAN, NATAL, SOUTH AFRICA.

CARBURETOR OR VAPORIZER PROVIDING MEANS FOR EASY STARTING OF INTERNAL-COMBUSTION ENGINES.

Application filed August 24, 1923. Serial No. 659,162.

To all whom it may concern:

Be it known that I, JAMES DOUGLAS MAIL, a subject of the King of England, residing at 142 West Street, Durban, Natal, Union of 5 South Africa (whose post-office address is 142 West Street, Durban, Natal, Union of South Africa), have invented certain new and useful Improvements in Carburetors or Vaporizers Providing Means for Easy 10 Starting of Internal-Combustion Engines, of which the following is a specification.

This invention has reference to carburetors and vaporizers with means for easy starting of internal combustion engines when 15 using either petrol or low grade fuel and especially the latter.

The device is to be placed preferably between the carburetor and the intake pipe of the engine.

20 Fig. 1 is a section and Fig. 2 is a half-sectional elevation of my invention.

The device consists of two flanges AA of aluminium alloy or of other suitable metal machined and drilled. The said flanges are 25 machined round so as to facilitate fitting on all types of cars, and are separated by the main body of the device.

Wound upon the main body is an element 30 B composed of any modern element wire, the length of the winding to be determined by the battery voltage of the car to be fitted with the device, allowing the maximum possible heat in the induction space internally but insufficient to reach the flash point of 35 the highest grade motor fuels.

The element is insulated from the main body by a sheet of mica or other insulating medium C and a second insulating sheet is fitted outside the element wire. This is then 40 lagged with asbestos cord E to direct the heat rays internally and a light metal casting F is fitted over the whole.

The ends of the element B are brought 45 through the housing being insulated by a bead G and pass through a fibre block D secured by set screws J attached to flanges A which block carries the terminal points H to the battery and switch connections.

The device can be arranged also for a 50 single wire system by grounding one end of

element B to one of the flanges AA secured by means of a small set screw.

The switch head is provided with a 10 amp. fuse not shown on drawing.

I, I are the Venturi holes for the passage of the gas.

I claim:—

1. A vaporizer attachment for internal combustion engines comprising a spool of metal having an aperture therethrough, a series of Venturi tubes arranged in said spool in a concentric circle around said aperture, an insulated electrical element wound round the body of said spool and terminals. 60

2. A vaporizer attachment for internal combustion engines comprising a spool of metal having an aperture therethrough, a series of Venturi tubes arranged in said spool in a concentric circle around said aperture, an electrical element wound round the body of said spool, insulating medium on the outer and inner sides of said element relatively to said spool, and terminals. 70

3. A vaporizer attachment for internal combustion engines comprising a spool of metal having an aperture therethrough, a series of Venturi tubes arranged in said spool in a concentric circle around said aperture, an electrical element wound round the body of said spool, insulating medium on the outer and inner sides of said element relatively to said spool, a lagging of asbestos cord outside the outer insulating medium, and terminals. 75

4. A vaporizer attachment for internal combustion engines comprising a spool of metal having an aperture therethrough, a series of Venturi tubes arranged in said spool in a concentric circle around said aperture, an insulated electrical element wound round the body of said spool, and a terminal. 90

In testimony whereof I have hereunto set my hand in presence of two subscribing witnesses this 20 day of July, 1923. 95

JAMES DOUGLAS MAIL.

Witnesses:

MURIEL JOYCE ELMY,
HUGH SENECA HOOD.
